UNITED STATES PATENT OFFICE

ALBERT BRANDL, AND CARL F. WEGNER, OF WAUSA, NEBRASKA

ENGINE GOVERNOR

Application filed July 2, 1929. Serial No. 375,438.

The present invention relates to an engine governor for controlling the speed of an internal combustion engine especially in automobiles, trucks, tractors and the like and the prime object of the invention resides in the provision of a governor structure of this nature which is controlled by the air current set up by the fan and the movement of the vehicle.

10 A still further very important object of the invention resides in the provision of an engine governor of this nature which is exceedingly simple in its construction, easy to install, strong and durable, not likely to easily become out of order, easy to adjust, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a side elevation of an engine showing our governor structure mounted thereon,

30 Figure 2 is a top plan view of the governor, Figure 3 is a rear elevation thereof,

Figure 4 is a sectional view taken substantially on the line 4—4 of Figure 2, and

35 Figure 5 is an elevation of the vane plate and its attached bar.

Referring to the drawing in detail it will be seen that the engine disclosed herein is of the conventional type including the block structure 5, cooling fan 6, and carburetor 7 among the usual other well known elements.

The letter A denotes a U-shaped bracket, the bight 8 of which is disposed vertically merging at its upper end into a relatively long horizontal leg 9 and at its lower end in a relatively short horizontal leg 10. The leg 9 is adapted to be fixed to the motor block 5 by means of one of the usual stud bolts associated therewith.

50 A shaft 11 is journaled through the legs 9 and 10 and has a crank 12 on the upper end

thereof and a crank 14 on the lower end thereof. A link 15 connects the crank 14 with the throttle valve of the carburetor 7. An L-shaped bracket 17 is mounted on the front of the engine block and has another L-shaped bracket 18 fixed thereto to provide spaced parallel arms a bolted together as at 19 and having a member 20 rockable therebetween with an opening 21 formed therein through which is extended a bar 22 on one end of 60 which is a vane plate 23 to be affected by the current of air set up by the fan 6.

The other end of the bar 22 has a link 25 engaged therewith and this link 25 is engaged with the crank 12. A bracket 26 is fixed to 65 the bracket A and a bolt 27 is engaged therewith by means of a thumb nut 28. A spring 29 is fixed to the bolt 27 and to the lever 22 and the tension of the spring 29 may be adjusted by turning the nut 28 as will be apparent.

From the above detailed description it will be seen that as the motor picks up speed the air current created by the fan 6 will be increased forcing the vane plate 23 rearwardly and rocking the bar 22 thereby pulling forwardly on the link 25 to swing forwardly on the crank 12 thus rocking the shaft 11 and swinging the crank 14 forwardly to pull on the link 15 which tends to close the throttle 80 valve of the carburetor 7.

The tension on the spring 29, of course, controls this governor and can be regulated to regulate the speed of the engine.

It is thought that the construction, operation, utility and advantages of this invention will now be quite apparent to those skilled in this art without a more detailed description thereof.

The present embodiment of the invention 90 has been disclosed in detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter 100

claimed or sacrificing any of its advantages.

Having thus described our invention, what we claim as new is:

1. A governor structure of the class described comprising a bracket adapted to be mounted on the front of an engine block, a bar, means for rockably mounting the bar in the bracket, and a vane on one end of the bar, a link engageable with the other end of the bar, a second bracket on the side of the engine block, a shaft rockable in the second bracket and having a crank at the upper end with which said link is engaged, a crank at the lower end of the shaft, means for operatively connecting the lower crank with the throttle valve of the carburetor.

2. A governor structure of the class described comprising a bracket adapted to be mounted on the front of an engine block, a bar, means for rockably mounting the bar in the bracket, and a vane on one end of the bracket, a link engageable with the other end of the bar, a second bracket on the side of the engine block, a shaft rockable in the second bracket and having a crank at the upper end with which said link is engaged, a crank at the lower end of the shaft, means for operatively connecting the lower crank with the throttle valve of the carburetor, spring means associated with the bar, and adjustable means associated with the spring.

3. A governor structure of the class described comprising a bar, means for rockably mounting the bar forwardly of the engine block of an internal combustion engine, a vane on one end of said bar, a shaft, means for rockably and vertically supporting said shaft to one side of the engine block, an operating connection between said bar and one end of said shaft, and means for operatively connecting the other end of said shaft with the throttle valve of a carburetor.

4. A governor structure of the class described comprising a bar, means for mounting the bar for rockable movement on a horizontal plane at the forward end of an engine block of an internal combustion engine, a rock shaft, means for mounting said rock shaft vertically on one side of the engine block, cranks on the upper and lower ends of said rock shaft, a vane on one end of said bar, means operatively connecting the other end of said bar with the crank on the upper end of said rock shaft, and means for operatively connecting the crank on the lower end of said rock shaft with the throttle valve of the carburetor and adjustable spring means operatively connected with said bar adjacent the last referred end of said bar.

60 In testimony whereof we affix our signatures.

ALBERT BRANDL.
CARL F. WEGNER.
